UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

YARN-CHANGING MECHANISM FOR KNITTING-MACHINES.

1,159,874.

Specification of Letters Patent.

Patented Nov. 9, 1915.

Application filed July 23, 1914. Serial No. 852,605.

To all whom it may concern:

Be it known that I, ROBERT W. SCOTT, a citizen of the United States, and resident of Boston, in the county of Suffolk and State 5 of Massachusetts, have invented certain new and useful Improvements in Yarn-Changing Mechanism for Knitting-Machines, of which the following is a specification.

My invention relates to mechanism for 10 changing the yarn in a knitting machine, and especially to devices of this nature capable of relatively frequent actuation to knit split foot, sectionally spliced and other forms of fabric.

15 I have illustrated my devices as an improvement on the mechanism shown and described in my application No. 845,844, filed June 18, 1914, but it will be evident that the new devices may be applied to other forms 20 of knitting machines.

In the accompanying drawings, Figure 1 is a vertical section showing the needles and 25 yarn guides and the devices for actuating them in side elevation; Fig. 2 is a plan view 30 of the actuating cams for said devices; Fig. 3 is a detail development of the needle cam ring; Fig. 4 is a view showing the needles.

In my said application I disclosed a yarn 35 changing and yarn splicing device comprising a series of yarn guide levers pivoted above and outside of the circle of needles in a circular knitting machine, and a device for lifting and lowering said yarn guide levers to change their yarns comprising a 40 series of independent thrust bars, in contact at their lower ends with a pattern cam surface. One of the yarn guide levers was, for 45 sectional splicing, provided on its under side with a lug against which the nose of its 50 thrust bar takes, so that said thrust bar when moved laterally elevates its yarn guide, to sharply remove the yarn thereof from the needles, the yarn being returned whenever 55 the bar is permitted to resume its normal lateral position. A cam carried by the web- 60 holder bed was provided to move the lug on the bar for this purpose, the pattern cam moving the bar lengthwise to determine whether or not its lug was in range of the 65 said cam, and hence to determine the timely 70 operation of the splicing device.

The present invention provides in addition 75 mechanism for an exchange of yarns occurring during rotary knitting in the same 80 course at a plurality of separated intervals

about the knit tube, provision being made to retain the yarn guide put out of work in its operative position after the yarn guide put into work shall have begun to feed a new 60 yarn to the needles. My new devices provide for an exchange of this nature occurring persistently at the same needle wales for course after course, to provide a longitudinally split or sutured fabric, such for instance as will be suitable for a substituted 65 fabric above the heel at the back of a stocking, or for a split foot, which may if desired be provided with a sole of heavier 70 yarn, or a yarn different in color or kind from the fabric of the leg and the top 75 thereof.

In the knitting machine chosen for illustration, the needle cylinder 260 and the attached web-holder bed 295 rotate with respect to the needle cams, yarn-feeding devices and other auxiliaries held in a relatively stationary position on the frame of the machine. My device is, however, independent of this arrangement, obviously being adapted to a machine in which the stitch 80 cams, yarn guide levers and actuating devices for the yarn guide levers rotate with respect to relatively stationary needles. The needle cams comprise stitch cams 6 and 7, 85 top center cam 8 and bottom center cam 9.

For the purposes presently to be explained, I provide the machine with a top center cam 8 cut away at 10 to remove a part of its lower apex, to permit needles having abnormally short butts to pass said cam at a 90 higher level than the remaining needles.

The yarn feeding devices comprise a series of yarn guide levers F journaled at 554 on the latch guard ring, which latch guard ring comprises a throat plate 559 upon which 95 said yarn guide levers rest, under the influence of springs f⁸ when they are in their normally operative position. The said devices are at the neighborhood of the plane central of the stitch cams shown in Fig. 3.

In my present device two or more yarn 100 guides, as F², F³ are provided with lugs 5 on their under faces to coöperate with the upper beveled ends of thrust bars 460^x and 460^y respectively associated with said yarn 105 guide levers. Each of the thrust bars occupies a slot in a comb 451 attached to a stud 450 fast in the frame of the machine, the upper end of the bar being guided by a comb 462 fixed to the frame of the machine. 110

Said thrust bars 460 have lateral freedom away from the axis of the machine at the comb 462, as illustrated in Fig. 1. The arrangement is such that a lateral movement 5 away from the axis of the cylinder 260 at the upper ends of the thrust bars will elevate the yarn guide levers by movement against the cam lug 5.

For the purposes of the present device, 10 means are provided to render the yarn guides F^2 , F^3 wholly inoperative, by elevating their thrust bars in the direction of their length, and at predetermined times to cause said yarn guides F^2 , F^3 to become operative 15 alternately at segments of the needles carried by the rotating needle cylinder, provision being made to overlap the yarns upon a few needles common to successive segments. Such a structure when repeated for 20 successive courses forms a longitudinal suture or union between parts of the fabric knit by the yarn of each of said yarn guides, the yarn out of work floating at the interior of the fabric until again introduced. For 25 a split foot stocking the points of union or sutures may be opposite points of the tube of fabric knit by one yarn guide forming the sole of the foot, the fabric knit by the other forming the instep or top of the foot.

I may provide upon any member of the organized machine moving in relation to or in unison with the needles means for moving the thrust bars 460 laterally for this purpose, but I prefer to employ cams g and h attached to the face of the web-holder bed 295, for instance by being seated in an annular recess formed in the bottom of the web-holder bed 295 upon which they are fastened by screws o .

The thrust bars 460 x and 460 y for the guides F^2 , F^3 may be alike with the exception of the provision on bar 460 x of a lug at a , and on bar 460 y of a lug b at respectively different vertical positions when the bottom 45 of the bars are in a certain position, and in the planes of the cams g and h respectively. This position of the bars 460 may be determined by eccentric limit stops 448 taking against the upper face of the comb 451.

The pattern drum 120 rotating in relation 50 to the times of the production of each article carries suitable cams 502 for elevating the bars when their yarn guides are to be thrown out of action, and for permitting the said bars to drop to the extent determined by the stops 448 when the split tube structure is to be made.

In the usual operation of knitting a stocking one of the yarn guides F will carry yarn 55 for the leg and another yarn guide F will be provided with a yarn suitable for the heel. Cams 502 on the drum 120 will maintain their guides F^2 , F^3 out of action during the knitting of the leg and during the knitting 60 of the heel, but at the close of the knit-

ting of the heel, said cams permit bars 460 x and 460 y to drop to feed a white yarn for the sole of the stocking and a black yarn for the instep of the stocking. The cam g , which is associated in a rotary sense with 70 the needles having short butts represented by the line n^2 will, when the bars for the guides F^2 , F^3 are dropped, react with the lug b controlling the lateral position of the bar 460 y for the guide F^3 to throw the back 75 yarn out of action during the passage of the short butt needles, while the cam h associated with the needles having long butts indicated by the line n' will react with lug a of the bar 460 x for the yarn guide F^2 to 80 throw out the white yarn for the sole, at said needles n' .

Referring now to Fig. 2, when the knitting of the heel is finished, the cams 502 run from under the end of both thrust bars, 85 causing the lugs a and b to drop until they contact with the upper faces of that cam g , h passing their location at this time. This movement is timed by placing cams 502 at the proper point to cause the lugs a 90 and b to encounter the lower cam g , thus permitting the bar 460 x and the guide F^2 carrying the white yarn to come to its adjusted position for feeding the white yarn. The position of the lug b and the bar 460 y 95 for the guide F^3 carrying the black yarn is then such as to bring it into the plane of c^2 , h , in which position the lug b will not encounter the periphery of its own cam g , but rests upon the upper face of the cam g . 100 The cam g is so formed as to permit lug b to drop, having at g' an intermediate level between the outer circumference p and the inner circumference q thereof, which lever precedes the leading slope h' of the cam h by an interval providing time for the dropping of the bar under the influence of spring f^8 into proper engagement with its own cam g . Cam h may be provided with a slope h^2 preceding the level g' to move 105 both the bars laterally to permit this motion of the bar carrying the lug b . The effect of the slope h^2 upon the bar 460 y carrying lug b is also to move it laterally against the lug 5 of its guide F^2 , to hold 110 said guide in position 2, Fig. 1, immediately above needles passing the throat plate at a normal level, and therefore to hold its yarn in a position at which it will not enter the needles until it has reached the lower position 1 permitted by a lower level q of its cam g , at slope g^2 . Immediately following the time of dropping the bars as described at the point indicated, that yarn guide F carrying the heel yarn will have been removed by a cam properly placed on the drum 120, to substitute yarn of the yarn guide F^2 for the heel yarn at this point. To secure taking the black yarn so entered and for other purposes, suture needles n^3 ar- 115 120 125 130

ranged to project above the other needles, as by having shorter butts than the normal short butt needles, are provided between the ends of the short butt and long butt series 5 as indicated in Fig. 2. By reason of the cut 10 in the top center cam 8, these needles maintain the advance caused by the preceding stitch cam 7 past the yarn-taking point, so that a yarn guide positioned at 2, Fig. 1, 10 by the lateral movement of its thrust bar when in contact with an intermediate level of the cams *g* or *h* will first encounter said suture needles. The black yarn of yarn guide *F*³ will therefore enter at the suture 15 needles. The white yarn of yarn guide *F*² after passage of said suture needles is immediately removed by elevation of guide *F*² to position 3 by the slope *h'* of the cam *h*, and the yarns remain in this position until 20 the next suture and exchange of yarns is to be formed, on the opposite side of the tube as shown. The cam *h* is at this point formed with an intermediate level *r* to drop the yarn guide *F*³ to position 2 to encounter 25 the advanced suture needles *n*³, followed by an incline *r'* to drop the yarn guide *F*³ to its lowest position 1, as shown in Fig. 1. The cam *g* at this point is of a symmetrically opposite form, as shown, to remove the 30 black yarn in two stages, the intermediate level of the cam *g* coinciding with the intermediate level *r* of the cam *h* at that point which is opposite the lugs *a* and *b* when the 35 yarn guides are in contact with the suture needles, as at *s*, Fig. 2.

It will be noticed that the overlapped ends of cams *g* and *h* provide a longer intermediate level at one suture than at the other, but this is without importance to the operation, 40 except for the described function of permitting the lug to be acted upon by the lower cam to reach its cam in a timely manner, the entry of the respective yarn guides *F*², *F*³ to their lowermost position after the 45 passage of the suture needles being precautionary only, to lower the yarn with respect to the needles traveling at a lower level at the yarn feed point, and thus to avoid accidental removal of the yarn in work caused 50 by slackness or vibration. Ordinarily the leading suture needle, having safely taken the yarn, its motion down the stitch cam will suffice to bring the yarn into the hooks of the following needles passing in a normal 55 position. When the toe of the stocking or the section of fabric near the toe is reached, bars 460^x and bars 460^y may be elevated

during the passage of the cam *g*, the yarn for knitting the remainder of the fabric being inserted by moving one of the guides 60 *F* just prior to this motion.

I do not herein claim the invention common to this application and my application Serial No. 851,931, filed July 20, 1914, which contains claims to the genus of which my present invention illustrates a species.

What I claim is:

1. In a knitting machine, the combination with needles of yarn guides, an instrument for each of said yarn guides movable 70 in one direction to render said guides respectively operative and inoperative, cams relatively movable with respect to said instruments and relatively fixed with respect to said needles acting directly on a part of 75 each of said instruments when they are positioned to render their guides operative to move each of said instruments in another direction to render their respective guides inoperative and operative alternately. 80

2. In a knitting machine, the combination with needles of yarn guides, a thrust-bar for each of said yarn guides, lugs on said thrust-bars, and means to lower and elevate said thrust-bars to render said guides re- 85 spectively operative and inoperative, cams rotating in horizontal planes for coaction with said lugs of each of a plurality of said thrust-bars when they are positioned in their lower position to move said thrust- 90 bars laterally to render their respective guides inoperative and operative alternately. 90

3. In a yarn changing device for knitting machines, the combination with yarn guides movable into and out of operative position 95 of thrust-bars for each of said yarn-guides and means for lifting and lowering two or more of said thrust-bars together to place their yarn guides into and out of operative position, in combination with cams in dif- 100 ferent horizontal planes rotating in the path of lugs carried by said thrust-bars, for operating said yarn guides, said cams having coincident high and low parts, and having coincident intermediate levels to permit 105 one of said lugs to pass to the lower cam to be actuated thereby.

In testimony whereof, I have signed my name to this specification in the presence of two subscribing witnesses.

ROBERT W. SCOTT.
